UNITED STATES PATENT OFFICE.

CEPHAS V. FITE AND CHARLES C. CODDINGTON, OF CHARLOTTE, NORTH CAROLINA.

GOVERNOR-CONTROLLED OR FORCE FEED FOR OIL ENGINES.

Application filed October 19, 1921. Serial No. 508,904.

To all whom it may concern:

Be it known that we, CEPHAS V. FITE and CHARLES C. CODDINGTON, citizens of the United States, residing at Charlotte, in the county of Mecklenburg and State of North Carolina, have invented new and useful Improvements in Governor-Controlled or Force Feed for Oil Engines, of which the following is a specification.

- 10 This invention relates to a governor controlled or force feed for oil engines, and one object of the invention is to positively regulate the volume of feed of oil fuel to the combustion chamber of an engine through 15 the medium of an injection pump mechanism having cooperating means for automatically changing the stroke of the pump piston and the oil volume and control the injected fuel in accordance with the power 20 needed, and also to inject the oil into the combustion chamber of the engine with economy and in the best possible condition for combustion and efficiency in the practical operation of the engine.
- 25 The improved governor controlled mechanism is intended for use with any form of engine combustion chamber adapted for heavy hydro-carbon oil or for the injection of the latter oil thereto, but is particularly 30 intended for application to automobile, motor boat and similar motor vehicle engines.

The invention consists in the construction and arrangement of the several parts which will be more fully hereinafter described and claimed.

In the drawings:

Fig. 1 is a sectional elevation of a governor controlled fuel feed for oil engines embodying the features of the invention and 40 showing part of the frame for supporting the same;

Fig. 2 illustrates perspective views of an eccentric and retaining means therefor, constituting the essential means under control 45 of a governor for automatically changing the stroke of the pump mechanism and the volume of oil injected by the latter in accordance with the work or load on the engine or motor;

50 Fig. 3 is a sectional side elevation of the eccentric, cam and shaft organization;

Fig. 4 is a diagrammatic view, illustrating in full and dotted lines of different forms the movements of the adjustable part of the mechanism.

To a suitable frame 5 that may be a part of an engine or motor adapted for the application of the improvement, or any other suitable supporting means, the improved governor mechanism is applied, the said 60 frame comprising, essentially, an upright arm 6 having an upper horizontal extension 7 with a slide seat 8 formed as a part thereof or secured thereto. The frame 5 also includes a lower horizontal arm 9 at right angles to the upright arm 6. Projecting outwardly from an intermediate portion of the upright arm 6 is a fulcrum stud 10, and in line with this stud an extension 11 horizontally intersects the said arm, the extension having a terminal arcuate head 12 with a segmental slot 13, the walls of which are struck from the center of the stud 10. On the stud 10 an elbow collar 14 of a bell crank lever 15 is mounted for adjustment, the bell 70 crank lever having an upwardly projecting short arm 16 and an outwardly projecting longer arm 17. Both arms 16 and 17 are fixed to the elbow or fulcrum collar 14 and the bell crank lever 15 as a whole serves as 80 means of adjustment in a manner which will be presently explained, the said arm 17 having a stud or analogous device 18 engaging the slot 13, and the part of this arm 17 extending outwardly beyond the stud 18 is 85 adapted to be provided with manual operating means or a mechanically actuated attachment in the form of a lever or other device. The means for operating the bell crank lever 15 as a whole through the arm 90 17 is not confined to any particular device, it only being necessary for the purposes of the invention to have the bell crank lever shifted as may be found necessary in accordance with the operation hereinafter explained. On the fulcrum stud 10 an actuating lever 19 is pivotally mounted and has a longitudinal slot 20 formed therein and carries a roller 21 in the end thereof opposite that engaging the stud 10. In the slot 20 a 100 slide block 22 is mounted for adjustment and has the lower end of a connecting rod or bar 23 pivotally attached thereto and also similarly connected to a slide 24 in the slide seat or guide 8 of the extension 7 at the upper end of the arm 6. Above the slide seat or guide 8 an injection pump 25 is supported in any suitable manner and formed with a piston chamber 26 having a vertically disposed piston 27 reciprocatingly mounted and 110

fixed at its lower end to the slide 24. A packing 28 is applied around the piston 27 and also a gland 29 for obvious non-leaking purposes. The frame of the pump 25 is formed 5 with an upper horizontal extension 30 having therein an oil bore or chamber 31 intersecting and extending across the upper extremity of the piston chamber 26. The piston chamber 26 and oil bore or chamber 31 10 are always in communication, and the outer end of the oil bore or chamber is formed with a flared outlet 32 at the terminal of the extension 30 adapted to be connected to the combustion chamber of an engine. The 15 inner terminal of the oil bore or chamber 31 is diametrically enlarged, as at 33, and communicates at its lower portion with a double check valve organization comprising a valve chamber 34, a valve seat 35 and a 20 lower supply nozzle 36, which is adapted to be connected to a source of fuel supply of heavy hydro-carbon oil or kerosene. The upper terminal of the bore 37 of the nozzle is formed with a valve seat 38 with which a 25 ball check valve 39 gravitatingly operates, the seat 35 above the check valve 39 having a bore 40 therethrough which is controlled by a ball check valve 41 in the valve chamber 34. From this construction it will be 30 seen that there is double check to return flow or back pressure on the oil entering the nozzle 36 from the supply source. Mounted in the bore 31 and extending across the piston chamber 26 and into the diametrically 35 enlarged portion 33 of the said bore or chamber 31 is a spray valve 42 having at one end a conical spray head 43 which is seated in the spray outlet 32 and at the opposite end is attached to a plunger washer or head 44 which 40 is located in the enlarged portion 33 of the oil bore or chamber 31, and between the plunger head 44 and the opposite end wall of the enlarged portion 33 of the oil bore or chamber 31 a spring 45 surrounds the spray 45 valve 42 and operates to restore the latter to normal position when relieved of pressure or after said valve may have been shifted by the action of the piston on the oil. It is obvious that the spray valve 42 will be moved and 50 the spray outlet 32 opened proportionately to the pressure exerted on the head 43 which snugly fits the said outlet but has sufficient surface exposed in the bore or chamber 31 adjacent to the outlet 32 to produce a practical 55 operation of the valve 42 under pressure of oil brought to bear on the said head, the valve 42 moving or shifting in its various opening positions against the resistance of the retracting spring 43. The rear end of 60 the enlarged portion 33 of the oil bore or chamber 31 is closed by a removable screw plug 46, the said plug giving access to the rear part of the oil bore or chamber 31 or the enlargement 33 for the purposes of adjustment and repair. The ball valve 39 has am-

ple play or movement in the upper end of the plug 36, a valve cavity 47 being formed in the plug of which the seat 38 is the base, for the operation of the said valve 39.

The horizontal arm 9 of the frame 5 provides suitable bearing supporting means for a power shaft 48 having a governor controlled or operated shaft 49 concentrically shiftable or reciprocable therein, the said governor controlled shaft being adapted to 70 have any suitable type of governor applied thereto, as well understood in the art, and moving in accordance with the speed of the governor. On the shaft 48 an eccentric 50 is fixed and peripherally engaged by a shiftable eccentric strap 51 having a cam or cam enlargement 52.

Extending transversely through the governor controlled shaft 49 and fixed to the latter, and also shiftable longitudinally in a slot 53 extending transversely relatively to the shaft 48, is a roller shaft 54 having on its outer end a roller 55 located in a diagonal slot 56 in an operating extension or member 57 of the eccentric strap 51, as shown by Fig. 3. The function of this roller shaft or rod 54 and roller 55 is to automatically shift the eccentric strap 51 on the periphery of the eccentric 50 in accordance with the operation of the governor controlling the movement 95 of the shaft 49, and whereby the stroke of the piston 27 will be modified, and also the volume of oil forced through the outlet 32 by way of the oil bore or chamber 31 will be correspondingly differentiated in accordance with the work performed, or the load on the motor, and the speed of operation of the engine which will be translated to the shaft 49 through the governor mechanism 100 associated with said shaft. The eccentric 50 and eccentric strap 51 are held in place on the shaft 48 by collars 50^a and 50^b, the collar 50^b being peripherally slotted as at 57, to receive the extension 57.

When the actuating lever 19 is horizontally disposed, as shown in Fig. 1, the piston 27 will reach the upward limit of its stroke when the roller 21 engages the highest part of the cam 52, the actuating lever 19 swinging on the fulcrum stud 10 and regularly following the contour of the cam from the highest to the lowest point and from the cam around the periphery of the eccentric strap 51, the said roller 21 when in engagement with the periphery of the eccentric strap or off the cam 52 causing the piston 27 to move to its lowest stroke position or lower limit of its stroke, and as the connecting rod or bar 23 is pivotally attached to the slide block 22 in the slot 20 of the actuating lever 19 and the slide 24, the various rising and falling movements of the said actuating lever, due to the roller 21 following the contour of the cam 52 and the periphery of the eccentric strap 51, will be 115 120 125 130

compensated for. As shown by Fig. 4, the lever 17 may be adjusted either above or below the horizontal plane shown by Fig. 1, the adjustment thereof above the horizontal plane being indicated by long and short broken lines 58, and which will result in a corresponding angular position shown by similar dotted lines 59, and through a link 60 pivoted to the upper end of the short arm 16 of the bell crank lever 15 and to the connecting rod or bar 23 above the slide block 22, the said latter slide block will be moved to the left in the slot 20 and correspondingly shift the connecting rod or bar 23 at an angle to the left of the vertical, and thereby lengthen the stroke of the piston 27 and the volume of oil that is indrawn into the injection pump 25, this adjustment of the several parts being indicated by long and short broken lines similar to the lines 58 and 59, as at 61, 62, 63 and 64. When the lever 15 is adjusted to bring the longer arm 17 below a horizontal plane as shown by the short dotted lines 65, and which is carried out through all the parts of the diagram in Fig. 4, the slide block 22 will be adjusted to the right of the vertical or towards the fulcrum stud 10 and correspondingly shift the connecting rod or bar 23 and shorten the stroke of the piston and at the same time reduce the volume of oil drawn into the injection pump 25. The downward strokes of the piston 27 set up a suction through the piston chamber by way of the enlarged portion 33 of the oil bore or chamber 31 and unseat the valves 41 and 39 in succession and cause the oil to be drawn upwardly through the bore 37 of the nozzle 36 and first enter the valve chamber 47 and then to pass through the bore 40 of the valve seat 35 into the valve chamber 34 and from the latter into the said enlarged portion 33 of the bore 31 to the piston chamber 26. Each upstroke of the piston 27 forces the oil into the injection pump as just specified in a corresponding direction, and by this means the valves 39 and 41 are firmly forced downwardly into closed position, and the oil is driven out through the bore or chamber 31 and opens the spray valve 42, to effect a spray thereof through the outlet 32 in accordance with the pressure of the piston against the oil, the quantity of oil sprayed through the outlet 32 depending upon the stroke of the piston 27 and at intervals corresponding to the rapidity of reciprocating motion of the piston.

The adjustment of the connecting rod or bar 23 by shifting the slide 22 in the slot 20 of the actuating lever 19 does not modify the stroke of the piston, but simply the volume of the oil drawn into and expelled from the injection pump 25. The stroke of the piston is regulated automatically through the movement of the governor con-

trolled shaft 49, which correspondingly moves the rod or shaft 54 and roller 55, so that through the diagonal slot 56 the eccentric strap 51 and cam 52 will be shifted circumferentially of the periphery of the eccentric 50, thereby giving the roller 21 in the end of the actuating lever 19 a different level, or raising and lowering it above the horizontal level of the said lever, as shown by the adjustment in Fig. 1. This automatic adjustment of the eccentric strap 51 and its cam 52 will, as above stated, change the stroke of the piston 27 by varying the throw of the lever 19, and will also regulate the volume of oil drawn into and expelled from the injection pump 25 in accordance with the work to be performed or the load on the motor.

The improved device may be applied to various types of engines where it is desired to use a heavy hydro-carbon oil as a fuel and to spray the oil into the combustion chamber of the engine in proportion to or in accordance with a predetermined oil charging action of the chamber or cylinder of the engine to which the improved attachment is applied.

What is claimed as new is:

1. In a governor controlled or force feed for oil engines of the class specified, the combination of an injection pump having a piston and spray valve and outlet, reciprocating means for the piston, adjustable components connected to the reciprocating means for modifying the length of stroke of the piston and the volume of oil drawn into and discharged by the pump, and a power shaft having a governor shaft extending therethrough and self-shifting devices cooperating with both shafts for automatically varying the stroke of the piston as well as the volume of oil drawn into and discharged from the pump in accordance with the load upon the engine to which the pump is attached.

2. In a governor controlled or force feed for oil engines, an injection pump having a valve supply inlet, a spray valve and discharge bore, a piston reciprocatingly mounted in the pump and controlling the indrawing and discharging of the oil from the pump, an actuating lever for the piston, connecting means between the piston and the actuating lever, adjusting means attached to the connecting means for varying the length of stroke of the piston and the volume of oil drawn into and discharged from the pump, automatically operating mechanism including a shiftable cam, an eccentric, and a power shaft, and intermediate means between the said mechanism and the connecting means for effecting a reciprocation of the piston of the pump in accordance with the high and low positions of the cam.

3. In a device of the class specified, an

injection pump having spray means and a piston, devices connected to and operating to reciprocate the said piston, adjusting means for the said devices to vary the length of 5 stroke of the piston and the volume of the oil drawn into and discharged from the pump, and automatically adjustable cam mechanism associated with the power shaft of the engine and engaged by a part of the 10 reciprocating devices to modify the speed of stroke of the piston and the volume of

oil drawn into and discharged from the pump.

In testimony whereof we have hereunto set our hands in presence of two subscribing 15 witnesses.
